UNITED STATES PATENT OFFICE.

ALEXANDER GEORGE STRATHERN, OF COATBRIDGE, SCOTLAND.

MACHINE FOR IMPRESSING METAL BARS BY ROLLING THE SAME.

1,108,272.

Specification of Letters Patent. Patented Aug. 25, 1914.

Application filed December 17, 1913. Serial No. 307,194.

To all whom it may concern:

Be it known that I, ALEXANDER GEORGE STRATHERN, a subject of the King of the United Kingdom of Great Britain and Ireland, and residing at Coatbridge, Lanarkshire, Scotland, have invented a certain new and useful Improvement in Machines for Impressing Metal Bars by Rolling the Same, of which the following is a specification.

10 This invention relates to machines of the type having more than two rolls, say four rolls, the outer tires, die rings or peripheries of which are of wedge section and are formed with protuberances and impressions 15 corresponding to the shape of chain links or other articles to be produced from metal bars of cruciform or other section.

The primary object of the invention is to provide an improved construction of machine of this type wherein the rolls are adapted to be readily changed or replaced.

In the accompanying drawing Figures 1 and 2 are elevations at right angles to each other of a chain-making machine constructed in accordance with the invention; Figs. 3 and 4 show a modification.

Like reference characters denote similar parts in the several figures of the drawing.

Referring to the drawing, the main frame 30 1 of the machine is constructed with two pairs of recesses 2, or housings, arranged in lines intersecting one another at right angles, *e. g.*, with two vertical recesses and two horizontal recesses leading from the center 35 of the frame. Within the recesses 2 are pivoted forked members including tines or arms 4 at the free ends of which operating rolls 5 are carried in bearings 6. Each roll has bevel gear teeth 5' formed on the sides 40 thereof which, when the rolls are in operative position, are designed to mesh with the teeth of their adjacent roll, that is to say, the rolls that are arranged at right angles to each other. By this arrangement it will 45 be apparent that all of the rolls will be operated simultaneously to thereby insure perfect alinement of the impression surfaces thereof.

The tines of each forked member may be 50 made integral (see the horizontally disposed members in Fig. 1) or fixedly connected, or each forked member may be divided, as indicated at 8, Figs. 1 and 3, into two elements secured on a common pivot disposed at the 55 bottom of the recess transversely thereof. To the free end of each tine 4 is bolted or

otherwise secured a cap piece 9 between which and the end of the tine is the bearing for the roll. The tines are retained in operative position by means of nuts and bolts, 60 the bolts passing through lugs 10 on the sides of the tines and through the main frame 1 of the machine. As shown, the forked members are adapted to be swung outward and inward on their pivots 11 65 simultaneously by means of worm gearing 12 and sector-shaped gear wheels 13 mounted on shafts rotatably mounted on the main frame of the machine and affording the pivots for the forked members. The driving shafts of the upper and lower rolls are adapted to be coupled and uncoupled at 14. When it is desired to change or remove the rolls, the forked members are swung outward from the main frame and the cap 70 pieces 9 detached, whereupon the rolls may be readily removed, and, if desired, other rolls may be substituted. The forked members may then be swung back to operative 75 position.

As shown in Figs. 3 and 4, each forked member is divided into two elements, the corresponding bearing 6 forming a separate piece which is secured by bolts 15 adapted to permit of the bearing to be easily removed, the bearings being fitted with cap pieces 9 secured by the bolts 15. When the rolls are in operative position, the elements with their bearings form a practically solid member. When it is desired to change or 80 remove the rolls, the forked members are swung outward from the main frame; the bearing secured to each upper element (in the case of the horizontal members) is removed and the upper element is swung backward toward the main frame, thus leaving a clear space above for removal of the roll. When the roll has been replaced, the upper 85 element is swung back into the same plane as the lower element and the bearing replaced and bolted rigidly to the upper element. The complete member is then swung 90 back to its working position and is retained in that position as in the previous case. The vertical members are operated in a similar 95 manner.

I claim:

1. A machine for impressing metal bars by rolling the same, comprising, in combination, a recessed frame, a plurality of rotatable rolls, pivoted members carrying said rolls, said members and rolls being housed 100

within said frame when in operative position and each being adapted to be oscillated on axes parallel to the axis of rotation of the roll carried thereby to shift the rolls into inoperative position.

2. A machine for impressing metal bars by rolling the same, comprising, in combination, a recessed frame, a plurality of cruciformly disposed fork-like members each 10 member being pivoted to said frame at one end and adapted to be oscillated out of the plane of said frame, bearing members carried by said members remote from the pivoted ends thereof, and rolls rotatably 15 mounted in said bearing members.

3. A machine for impressing metal bars by rolling the same, comprising, in combination, a frame formed with recesses, divided forked members, and rolls carried by said 20 forked members, said forked members and rolls being housed in said recesses when in operative position and adapted to be oscillated out of said recesses to shift said rolls into inoperative position.

25 4. A machine for impressing metal bars by rolling the same, comprising, in combination, a frame formed with recesses, forked members, and rolls carried by said forked members, said members and rolls housed in 30 said recesses when in operative position and adapted to be oscillated simultaneously out of said recesses to bring said rolls into inoperative position.

35 5. A machine for impressing metal bars by rolling the same, comprising, in combination, a frame, a plurality of rotatable rolls, cruciformly disposed forked members supporting said rolls, each forked member pivoted to said frame on an axis parallel with 40 the axis of rotation of the roll carried thereby and adapted to be swung outwardly on

its pivot, whereby said rolls are shifted to inoperative position.

6. A machine for impressing metal bars by rolling the same, comprising, in combination, a frame formed with recesses, divided forked members pivotally mounted in said recesses, and rolls carried by said forked members, said forked members and rolls being housed in said recesses when in operative position and adapted to be oscillated out of said recesses to shift said rolls into inoperative position.

7. A machine for impressing metal bars by rolling the same, comprising, in combination with a frame, cruciformly disposed forked members pivotally mounted in said frame, a rotatable impressing roll carried at the outer end of each forked member, said forked members being pivoted on axes 50 parallel with the axis of rotation of the said rolls, and means for simultaneously swinging said forked members outwardly on their pivots.

8. A machine for impressing metals bars by rolling the same, comprising, in combination with a recessed frame, a plurality of forked members journaled therein, coacting forming rolls journaled in said members, each of said rolls having bevel gear teeth 65 formed on the opposite sides thereof which are adapted to mesh with the teeth of its adjacent roll, and means for simultaneously swinging said forked members outwardly from the frame, for the purpose specified.

In testimony whereof I have signed my name to this specification in the presence of two subscribing witnesses.

ALEXANDER GEORGE STRATHERN.
